UNITED STATES PATENT OFFICE.

AUSTIN D. EBERLY, OF SPOKANE, WASHINGTON.

STARTING AND STOPPING MECHANISM FOR ENGINES.

1,215,639.

Specification of Letters Patent. Patented Feb. 13, 1917.

Application filed March 4, 1916. Serial No. 82,194.

To all whom it may concern:

Be it known that I, AUSTIN D. EBERLY, a citizen of the United States, residing at Spokane, in the county of Spokane and 5 State of Washington, have invented certain new and useful Improvements in Starting and Stopping Mechanisms for Engines, of which the following is a specification.

This invention relates to new and useful 10 improvements in starting and stopping mechanisms for engines, and more particularly to engines utilizing electric starters, and the primary object of the invention is to provide a device which will automatically 15 start the motor at a predetermined temperature and also stop the same automatically at a predetermined increased temperature.

It is a well known fact that considerable 20 difficulty is experienced by motorists in starting motors during the cold periods of the year and it very often happens that water in the radiators becomes frozen and causes considerable damage to the motor.

25 My invention contemplates the provision of a thermostatic switch mechanism which, at the predetermined low temperature, will operate the electric starter of the automobile and cause the engine to be started and 30 which will further operate to stop the motor when the latter has become heated to a predetermined higher temperature.

Still another object of the invention resides in the provision of an auxiliary magnetic switch operating with the starter of the engine separately from the starting switch stopper of the machine.

A still further object resides in the provision of an ignition switch in direct coöperation with the thermo-operated switch to coöperate with the vibrator, whereby to 40 send a spark to the engine.

A still further object resides in providing a device which is adapted to be adjustably applied to the exhaust pipe of the engine whereby to be actuated by the heat emanating therefrom, the adjustability of the device serving as a means to enable the device to be moved nearer or farther from 45 the heat, as may be desired for the thermal means.

Still another object resides in the provision of a device of simple and durable construction, inexpensive to manufacture and

one which will be very efficient and useful in 55 operation.

With these and other objects in view, my invention consists in the novel features of construction, combination and arrangement of parts, as will be hereinafter referred to 60 and more particularly pointed out in the specification and claims.

In the accompanying drawings, forming a part of this application:—

Figure 1 is a diagrammatic view showing 65 the method of attachment and the wiring of the complete device applied to use on an automobile.

Fig. 2 is an elevation of the interior of the thermo operated switches, the cover being removed from the device. 70

Fig. 3 is a detail section through Fig. 2 as seen on the line 3—3.

Fig. 4 is a perspective view of the ignition switch removed. 75

Fig. 5 is an inverted perspective view of the thermo switch mechanism removed.

In describing the invention I shall refer to the drawings, in which similar reference characters designate corresponding parts 80 throughout the several views, and in which 1 designates an automobile of the usual or any preferred type having a motor 2 suitably mounted thereon, the latter having the electric starter 3 coöperating therewith, said 85 starter being manually operated by means of a starting switch 5. This starting switch is mounted, as usual, on the dashboard 4 of the automobile, and the switch connects with the starter by means of the 90 wire 6. An ignition switch 7 of the usual type is also suitably mounted on the automobile, the same connecting through the medium of a wire 8 through a vibrator 9 and a wire 10 which also leads from the 95 switch 7 is grounded, as usual, on the frame of the automobile.

The thermo operated switch is composed of a frame or casing 11 which is secured by means of straps or clamps 12 to the exhaust pipe 13 of the motor, and wing portions 14 are provided on the casing 11 whereby said straps or clamps may engage the same. Set screws 15 are adjustably carried on the wing portions to enable the casing 11 to be 100 drawn nearer or farther from the exhaust pipe, as may be desired.

A pair of bearing plates or the like 105

- are secured to the inner wall of the casing 11 by means of the brackets or the like 17 and suitably arranged between said bearing plates is a thermal expanding and contracting spring 18 which is designed to operate a shaft 19 which is also mounted in the bearing plates 16. Attached to the outer end of the shaft 19 is a lever 20, one end of which is engaged with a link 21, 5 said link being provided intermediate of its ends with a turnbuckle 22. The opposite end of the link 21 is connected to a switch lever 23, the latter being fulcrumed intermediate of its ends at a point designated at 10 24. The lower end of the lever 23 is provided with a pair of contacts 25 which are designed to coöperate with a pair of contact posts 26 which are mounted in the side wall of the casing 11.
- 20 Pivottally connected to the lever 23 just above its fulcrum point is a linking lever 27 which has its ends compoundly curved, the lower end thereof being slightly reduced in cross-section as designated at 29. A turnbuckle 28 is also provided on the link 27 to accommodate adjustment of said link for 25 obvious purposes. A post 30 is suitably mounted in the bottom of the casing 11 to extend vertically and has its upper end provided with an opening to receive therethrough the reduced lower end 29 of the link 27. A roller 31 is provided at this upper end of the post to receive said reduced end 29 in contact therewith.
- 35 Mounted in the adjacent side wall of the casing 11 is a post 32 which is bifurcated and designed to act as a fulcrum for a forked lever 33, as clearly shown in Figs. 2, 3 and 4 of the drawings. A spring member 40 34 has one end thereof connected to the lower-end of the link 27 and its opposite end is connected with the upper portion of the lever 33 as clearly shown in Figs. 3 and 4. The extreme upper portion of the lever 33 45 is provided with a pair of contacts 35 which are designed for contact with a pair of contact posts 36, the latter being suitably mounted in the adjacent side wall of the casing 11.
- 50 Leading from the contact posts 26 are the wires 37 which connect with a pair of contacts on a magnetic switch member 38, the latter being interposed between the thermo switch and the starter 3.
- 55 It will be readily understood that when the temperature reaches a predetermined degree and causes the contraction of the spring member 18, the lever 23 will be operated to complete the circuit above mentioned whereby to start the engine automatically. It will be seen from Fig. 1 that the connection between the magnetic switch 38 and the starter 3 is had through the medium of wires 42 which intersect the wires 6 beyond the starting switch 5, so that the start-

ing mechanism may be actuated through this mechanism, regardless of the operation of said switch 5.

At the same time the lever 23 is actuated upon the contraction of the spring 18 the lever 33 is, of course, actuated to engage the contacts 35 and 36. The contact posts 36 have the wires 43 leading therefrom, and the same respectively engage wires 8 and 10 leading from the ignition switch. Hence at the time the starter 3 is operated, a spark is also caused to be made in the engine, so that the operation of said starter of course causes the engine to be operated.

It will thus be seen that the engine is set in operation automatically, and after running for a certain length of time, the heat emanating therefrom will cause the spring 18 to expand, which obviously opens the circuits above mentioned, and stops the motor. The starter switch 23 is opened by the first expansion of the thermal spring 18 serving to cut off the starter. The ignition switch 35 remains in contact until full expansion of the thermal spring 18 is had and the motor has reached the desired temperature. In this manner it will be seen that the freezing of the engine will be prevented, it being of course understood that the device is set for operation at a temperature above the freezing point. In order to afford a means for conveying the heat to the thermal switch mechanism, a copper conductor (not shown) may be provided, and I have provided an opening 44 in the rear wall of the casing 11 whereby this conductor may be introduced into the device. The conductor when used will, of course, be arranged for contact with the exhaust pipe.

From the foregoing description of the construction of my improved mechanism, the operation thereof and the manner of applying the same to use, will be readily understood, and it will be seen that I have provided a simple, inexpensive, and efficient means for carrying out the objects of the invention.

While I have particularly described the elements best adapted to perform the functions set forth, it is obvious that various changes in the form, proportion and in the minor details of construction may be resorted to without departing from the spirit or sacrificing any of the principles of the invention.

Having thus described my invention, what I claim is:

1. In a thermal controlled electrical switch mechanism, a support for the mechanism, an expanding and contracting means, a switch lever adapted to be actuated by said means, contact means carried by said lever, engaging contact means therefor; an additional switch lever fulcrumed in said support, contact means carried by the last

mentioned lever, engaging contact means therefor; a linking member for connecting said levers, and a yielding connecting member for connecting said linking member and 5 said additional switch lever.

2. In a thermostatic switch of the class described, a casing, an expanding and contracting spring suitably mounted therein, a shaft operated by said spring, a switch lever 10 fulcrumed within the casing and having adjustable connection with said shaft, a pair of contacts carried on one end of said switch lever, a pair of contact posts mounted in the casing for engagement therewith, an additional switch lever fulcrumed within the 15 casing, a linking member connected with the first mentioned switch member, and a yielding connection between said linking member and said last mentioned switch lever, whereby to operate the latter upon the operation 20 of the first mentioned switch lever.

3. In a switch member of the class described, a casing adapted to be secured adjustably to an exhaust pipe, an expanding 25 and contracting spring member suitably

mounted in said casing, a switch lever fulcrumed within said casing and having adjustable connection with said spring member, electrical contact members on said lever, additional contact members on said casing 30 for engagement therewith, a fork-like switch lever fulcrumed within said casing and having contact members at one end thereof, additional contact members carried on the casing adapted for engagement with 35 the last mentioned contact members, a linking member connected at its one end with said first mentioned switch lever, a guiding support for the opposite end of said linking member, the last mentioned end of said 40 linking member being directed between the arms of said second mentioned switch lever, and a coil spring member engaged with the lower end of said linking member and the crown of said fork-like switch lever, whereby to operate the latter upon the operation 45 of the first switch lever.

In testimony whereof I affix my signature.

AUSTIN D. EBERLY.
